FUSE CONSTRUCTION

William O. Schultz, South Milwaukee, Wis., assignor to Line Material Company, South Milwaukee, Wis., a corporation of Delaware

Application November 20, 1936, Serial No. 111,827

16 Claims. (Cl. 200—115)

This invention relates to a fuse construction and is particularly directed to a fuse construction associated with a transformer or other electrical device.

5 This invention is intended to provide a fuse construction which is particularly useful on a single bushing transformer which is now quite common for rural service. These transformers are made up with only one primary bushing, the 10 other side of the primary winding being solidly grounded to the transformer case.

Objects of this invention are to provide a fuse construction in which the fuse structure is carried by or supported from the transformer bushing, in which an expulsion fuse tube is so mounted that the expelled gases and metallic vapors are directed away from the casing.

Further objects are to provide a novel form of construction in which the fuse tube performs 20 a two-fold function, as it acts as an insulating member to insulate one contact from the other contact and also acts as a support for the spark gap or surge protecting means, and in which the spark gap carried by the fuse tube is of the 25 expulsion tube type and is associated with a stationary electrode to insure proper spacing, irrespective of inaccuracies in the precise alignment of the parts.

Further objects are to provide a construction 30 in which an expulsion type of fuse is readily applied to or removed from the contact of a single bushing transformer, in which provision is made for detachably locking the fuse construction to the contact of the single bushing transformer, in 35 which provision is made for detachably connecting the opposite end of the fuse tube to a live conductor, and in which the clamping means for attaching or detaching the fuse tube and for connecting it to a line wire may be operated by a 40 switch stick, the fuse itself being thereafter removed either by tongs or by hand.

Further objects are to provide a construction of combined fuse tube and surge protection means which is cheap to manufacture and simple 45 in construction and which has very few parts.

Embodiments of the invention are shown in the accompanying drawings, in which:

Figure 1 is a side elevation, partly in section, showing the fuse tube in place.

50 Figure 2 is a horizontal fragmentary view, with parts in section.

Figure 3 is a view of a modified form of construction, such view corresponding to Figure 2.

Referring to Figures 1 and 2, it will be seen 55 that the transformer housing 1, which is of

metal, is provided with a rigidly mounted, insulating bushing 2 projecting upwardly therefrom and terminating in a threaded contact stud 3. This contact stud 3 receives the conductor from one side of the primary of the transformer and is interlocked with the rigidly mounted insulating bushing 2. This contact stud receives the cap nut 4 which carries the contact or lug 5. This contact 5 is of rectangular construction, as is apparent from Figure 2. 10

The fuse tube 6 is provided with an apertured contact 7 at one end provided with a downwardly extending, internally threaded boss or sleeve 8 and with an upwardly projecting connector receiving bar or portion 9. The other end of the 15 fuse tube or the effective open end thereof is provided with a contact 10 which has an integrally formed, laterally offset projection 11 provided with a rectangular aperture 12 for the reception of the lug or contact 5. The member 20 11 is provided with a locking screw member 13 equipped with an eyelet 14 so that it may be handled by a switch stick. The contact 10 also carries a threaded stud 15 which receives the thumb nut 16 by means of which the leader 17 of 25 the fuse link may be attached.

The fuse link may comprise a small size strain-resisting wire 18, which may be of iron or steel, and a section 19 formed of low fusible alloy. A spring 20 holds the strain wire 18 in tension. 30 The other end of the spring 20 is attached to a stud 21 provided with a head 22 bearing against the outer side of the contact 7, as shown most clearly in Figure 1.

An insulating sleeve 23 is threaded into the 35 boss 8 and an upper electrode or spark member 24 is secured to the contact 7 and projects downwardly into the tube or sleeve 23. The rod or spark member 24 is spaced from the side walls of the sleeve 23 and also stops a considerable 40 distance above the lower end of the sleeve 23. The lower electrode or surge protection means or spark gap comprises a stem 25 terminating in an upper disk 26, the disk presenting substantial area towards the tube 23 so that precise 45 alignment of the parts is not necessary, as small variations will be taken care of as the tube 23 will under all conditions be positioned above the disk 26.

A leader 27 is clamped by means of the split 50 connector 28 to the stem 25 of the contact 7. The other end of the leader is secured to a clamping member or live wire clamp 28 which may comprise an upper hooklike member 29 adapted to hook over the line wire 30, and a lower clamp- 55

ing screw 31 provided with an eyelet portion 32. When an overload occurs, the section 19 formed of a low melting point alloy is ruptured and immediately the strain wire 18 is ruptured. The spring 20 increases the separation of the parts and the violently expelled gases blow any remaining portion of the leader or fusible sections 18 and 19 outwardly from the fuse tube, thus insuring extinction of the arc within the tube 10 and rapid breaking of the circuit.

Thereafter the fuse tube may be detached from the contact 5 or support by means of a switch stick cooperating with the eyelet 14 and the clamp eyelet 32 may similarly be operated by a 15 switch stick to detach the leader 27 from the live wire or line wire 30.

The device may be re-fused and may be replaced in the reverse manner.

It is to be noted that normally the head 22 20 of the fuse link, see Figure 1, closes the aperture in the contact 7 and is held in engagement with such contact by means of the spring 20.

It will be seen that surge protection is provided under all conditions, even after the fuse 25 has ruptured, as any surge that may occur will be taken care of by the spark gap members 24 and 26. The arc will be immediately extinguished as the hot gases are violently blown from the tube 23 and thus extinguish the arc.

30 The fuse tube itself forms the support for the spark gap member and also acts as an insulating spacing member for the two contacts connected by the fuse link. Also it is to be noted that the fuse tube is very easily applied to or removed 35 from the transformer.

Other types of fuse tubes could be employed, for example the type shown in Figure 3. In this form of the invention, the fuse tube 33 is provided with a contact 34 which has a threaded 40 sleeve equipped with a cap nut or clamping nut 35 which clamps the head or button 36 of the fuse link to the contact 34. The fusible section is indicated at 37 and the leader at 38.

This leader is clamped beneath the thumb 45 nut 16' which is threaded on the stem 15' of the contact member 10'. This contact member has a rectangular slot for the reception of the contact 5 and may be locked thereto by means of the screw member or clamping member 13' which 50 is provided with the eyelet portion 14', all as previously described.

The fuse tube may be similar in other respects to the form shown in Figures 1 and 2 and carries a spark gap member, as previously described, 55 such member, however, not being visible in Figure 3.

An overload causes the fuse to act as an ordinary type of expulsion fuse. This form of the invention may be applied to and removed from 60 the transformer in the same manner as that previously described.

It will be seen that a novel form of fuse construction has been provided which is particularly adapted for use on single bushing transformers 65 and which is so made that a minimum number of parts are employed, the fuse tube acting in the double capacity of the insulator for spacing the contacts and also for the support for the spark gap or surge protection means.

70 Although this invention has been described in considerable detail, it is to be understood that such description is intended as illustrative rather than limiting, as the invention may be variously embodied and is to be interpreted as claimed.

I claim:

1. In an apparatus of the class described, a stationary contact, supporting means for said stationary contact, a fuse tube having a contact provided with means cooperating with said stationary contact, means for removably holding the means which cooperates with said stationary contact to said stationary contact, said fuse tube being electrically connected to and mechanically supported from said stationary contact, said fuse tube including an insulating tubular body portion projecting outwardly from the contact of said fuse tube and having a terminal contact held in spaced relation to said supporting means and the first mentioned contact of said fuse tube, and a fuse link joining the contacts of said fuse tube.

2. In an apparatus of the class described, a stationary contact, supporting means for said stationary contact, a fuse tube having a contact provided with means cooperating with said stationary contact, means for removably holding the means which cooperates with said stationary contact to said stationary contact, said fuse tube being electrically connected to and mechanically supported from said stationary contact, said fuse tube including an insulating tubular body portion 25 projecting outwardly from the contact of said fuse tube and having a terminal contact held in spaced relation to said supporting means and the first mentioned contact of said fuse tube, a fuse 30 link joining the contacts of said fuse tube, and conductor receiving means carried by said terminal contact.

3. In an apparatus of the class described, supporting means, a stationary contact carried by 35 said supporting means, a fuse tube having a contact provided with means cooperating with said stationary contact, means for removably holding the means which cooperates with said stationary contact to said stationary contact, said 40 fuse tube being electrically connected to and mechanically supported from said stationary contact, said fuse tube including an insulating tubular body portion projecting outwardly from the contact of said fuse tube and having a terminal contact held in spaced relation to said supporting means and the first mentioned contact of said fuse tube, a fuse link joining the contacts of said fuse tube, and spark gap means, 45 one portion of said spark gap means being supported from and carried by the terminal contact of said fuse tube and the other portion of said spark gap means being carried by said supporting means.

4. In an apparatus of the class described, supporting means, a stationary contact carried by 55 said supporting means, a fuse tube having a contact provided with means cooperating with said stationary contact, means for removably holding the means which cooperates with said stationary 60 contact to said stationary contact, said fuse tube being electrically connected to and mechanically supported from said stationary contact, said fuse tube including an insulating tubular body portion 65 projecting outwardly from the contact of said fuse tube and having a terminal contact held in spaced relation to said supporting means and the first mentioned contact of said fuse tube, a fuse link joining the contacts of said fuse tube, and spark gap means formed of two parts, one 70 part consisting of a sleeve and an internal electrode carried by said terminal contact and the other part consisting of a disk like member carried by said supporting means and spaced from said sleeve, said internal electrode being spaced

a material distance from the lower end of said sleeve.
5. In an apparatus of the class described, supporting means, an insulating bushing carried by said supporting means and forming a unitary portion with said supporting means, a rectangular stationary contact carried by said insulating bushing, a fuse construction comprising a fuse tube having a first and a second contact, said first contact having a rectangular aperture for the reception of said stationary contact, gripping means for holding said first contact to said stationary contact to electrically connect said fuse tube thereto and to mechanically support said fuse tube therefrom with said fuse tube projecting from said stationary contact, conductor receiving means connected to said second contact, and a fuse link joining said first and second contacts.

20 6. In an apparatus of the class described, supporting means, an insulating bushing carried by said supporting means and forming a unitary portion with said supporting means, a rectangular stationary contact carried by said insulating bushing, a fuse construction comprising a fuse tube having a first and a second contact, said first contact having a rectangular aperture for the reception of said stationary contact, gripping means for holding said first contact to said stationary contact to electrically connect said fuse tube thereto and to mechanically support said fuse tube therefrom with said fuse tube projecting laterally from said stationary contact, conductor receiving means connected to said second contact, and a fuse link joining said first and second contacts.

25 7. In an apparatus of the class described, supporting means, an insulating bushing carried by said supporting means and forming a unitary portion with said supporting means, a rectangular stationary contact carried by said insulating bushing, a fuse construction comprising a fuse tube having a first and a second contact, said first contact having a rectangular aperture for the reception of said stationary contact, gripping means for holding said first contact to said stationary contact to electrically connect said fuse tube thereto and to mechanically support said fuse tube therefrom with said fuse tube projecting from said stationary contact, conductor receiving means connected to said second contact, a fuse link joining said first and second contacts, and spark gap means formed of two portions, one of said portions being carried by said supporting means and the other of said portions being supported from the second contact of said fuse tube in spaced relation to said first mentioned portion.

30 8. In an apparatus of the class described, supporting means, an insulating bushing carried by said supporting means and forming a unitary portion with said supporting means, a rectangular stationary contact carried by said insulating bushing, a fuse construction comprising a fuse tube having a first and a second contact, said first contact having a rectangular aperture for the reception of said stationary contact, said first contact binding against said stationary contact to electrically connect said fuse tube thereto and to mechanically support said fuse tube therefrom with said fuse tube projecting laterally from said stationary contact, conductor receiving means connected to said second contact, a fuse link joining said first and second contacts, and a spark gap means formed of two portions, one of

said portions being carried by said supporting means and the other of said portions being supported from the second contact of said fuse tube in spaced relation to said first mentioned portion.

35 9. In an apparatus of the class described, supporting means, a bushing rigidly carried by said supporting means and projecting therefrom and having a stationary contact, an expulsion fuse construction comprising a fuse tube having a first and a second contact, said first contact being 10 apertured for the reception of said stationary contact, clamping means for locking said first contact to said stationary contact, said fuse tube being mechanically supported by and extending from said stationary contact, a fuse link joining 15 said first and second contacts, a flexible leader connected to said second contact, and line wire clamping means secured to said flexible leader.

40 10. In an apparatus of the class described, supporting means, a bushing rigidly carried by said supporting means and projecting therefrom, a stationary contact carried by said bushing, a fuse construction, said fuse construction comprising an expulsion fuse tube having a first contact and a second contact, means for locking said first contact to said stationary contact, a fuse link joining said first and second contacts, line wire connecting means joined to said second contact, a spark gap member rigidly carried by said second contact and projecting towards said supporting means, and a second spark gap member carried by said supporting means and presented towards said first spark gap member.

45 11. In an apparatus of the class described, supporting means, an insulating bushing projecting therefrom, a stationary contact carried by said bushing, a fuse construction comprising a fuse tube having a first contact and a second contact, said first contact having an apertured portion for the reception of said stationary contact, readily releasable clamping means for clamping said first contact to said stationary contact, a fuse link extending from said second contact through said fuse tube to said first contact, a clamping nut carried by said first contact 40 for clamping said fuse link, said fuse tube being mechanically supported from said stationary contact and projecting laterally therefrom, and detachable line wire connecting means connected to said second contact.

50 12. In an apparatus of the class described, supporting means, an insulating bushing projecting therefrom, a stationary contact carried by said bushing, a fuse construction comprising a fuse tube having a first contact and a second contact, said first contact having an apertured portion for the reception of said stationary contact, readily releasable clamping means for clamping said first contact to said stationary contact, a fuse link extending from said second contact 45 through said fuse tube to said first contact, a clamping nut carried by said first contact for clamping said fuse link, said fuse tube being mechanically supported from said stationary contact and projecting laterally therefrom, detachable line wire connecting means connected to said second contact, an insulating sleeve carried by said second contact and projecting towards said supporting means and spaced therefrom, and a spark gap electrode secured to said second contact and located within said sleeve and spaced from the end of said sleeve and forming one member of a spark gap, the other member of said spark gap being carried by said supporting means and spaced from the end of said sleeve.

13. In an apparatus of the class described, supporting means, an insulating bushing projecting therefrom, a stationary contact carried by said bushing, a fuse construction comprising a fuse tube having a first contact and a second contact, said first contact having an apertured portion for the reception of said stationary contact, means carried by said first contact for manipulation by a switch stick, said means temporarily locking said first contact to said stationary contact, a fuse link extending from said second contact through said fuse tube to said first contact, said fuse tube being mechanically supported from said stationary contact and projecting laterally therefrom, a flexible leader secured to said second contact, and line wire clamping means for manipulation by a switch stick, said line wire clamping means being attached to said flexible leader.
14. In an apparatus of the class described, supporting means, an insulating bushing rigidly carried by said supporting means and forming a unitary portion with said supporting means, a stationary contact carried by and interlocking with said bushing to prevent rotation of said stationary contact with respect to said bushing, a fuse construction comprising a fuse tube having a first contact and a second contact, said first contact having means interlocking with said stationary contact for supporting said fuse tube from said stationary contact and for precluding rotation of said fuse tube with reference to said stationary contact, said fuse tube being electrically connected to said stationary contact and mechanically supported laterally from said stationary contact, conductor receiving means connected to said second contact, a fuse link joining said first and second contacts, and spark gap means formed of two portions, one of said portions being carried by said supporting means and the other of said portions being supported from said second contact of the fuse tube in spaced relation to said first mentioned portion.
15. In an apparatus of the class described, supporting means, an insulating bushing rigidly carried by said supporting means and forming a unitary portion with said supporting means, a stationary contact carried by and interlocking with said bushing to prevent rotation of said stationary contact with respect to said bushing, a fuse construction comprising a fuse tube having a first contact and a second contact, said first contact having means interlocking with said stationary contact for supporting said fuse tube from said stationary contact and for precluding rotation of said fuse tube with reference to said stationary contact, said fuse tube being electrically connected to said stationary contact and mechanically supported laterally from said stationary contact, conductor receiving means connected to said second contact, a fuse link joining said first and second contacts.
16. The combination of a rigidly mounted terminal member and an insulating bushing surrounding said member, a terminal cap rigidly mounted on said bushing and secured to said member, said cap having a rectangular contact lug, an expulsion fuse tube having at one end a terminal collar provided with a laterally projecting rectangularly apertured sleeve receiving said lug and having at the other end a terminal collar provided with an arcing rod projecting from said fuse tube, said fuse tube projecting laterally from said bushing, an insulating tube surrounding said rod, an arcing member adjacent said insulating tube and spaced from said tube and rod, and connecting means for electrically connecting said fuse tube with an electric line conductor.

WILLIAM O. SCHULTZ. 40
